DESIGN FOR A SHOWCASE

Henry C. Chase, Chicago, Ill.

Application December 15, 1945, Serial No. 124,760

Term of patent 14 years

(Cl. D80—11)

To all whom it may concern:

Be it known that I, Henry C. Chase, a citizen of the United States, residing at Chicago, in the county of Cook and State of Illinois, have invented a new, original, and ornamental Design for a Showcase, of which the following is a specification, reference being had to the accompanying drawing, forming a part thereof.

In the drawing:

Fig. 1 is a perspective view of the showcase embodying the design.

Fig. 2 is a front elevational view; and

Fig. 3 is a side elevational view.

I claim:

The ornamental design for a showcase, substantially as shown.

HENRY C. CHASE.
